ABSTRACT OF THE DISCLOSURE

There is disclosed a crossed-field discharge device comprising an envelope enclosing an anode structure which defines an axially extending space, an electron emissive cathode structure disposed in the axially extending space and a pair of identical composite pole pieces disposed adjacent to the opposite ends of the anode structure, each composite pole piece including an inner annular pole piece disposed internally of the envelope and an outer annular pole piece disposed externally of the envelope in radial alignment with the inner pole piece, the outer diameter of the composite pole piece being from about 2.0 to about 2.5 times the axial gap between the internal pole pieces.

The present invention relates to an improved crossed-field discharge device and particularly to an improved magnetic pole structure therefor, and to microwave assemblies incorporating the improved crossed-field discharge device therein.

It is a general object of the invention to provide a new and improved crossed-field discharge device for use at microwave frequencies, which device incorporates therein an improved magnetic pole structure providing a more uniform field through the interaction space all in a compact and inexpensive crossed-field device.

Another object of the invention is to provide an improved cross-field discharge device comprising an envelope an anode structure disposed in the envelope and defining an axially extending space, an axially extending cathode structure disposed in the axially extending space and cooperating with the anode structure to define an axially extending annular interaction space therebetween, the cathode structure including an electron emissive element disposed within the anode structure and adjacent to the inner portion of the interaction space, a pair of internal magnetic pole pieces disposed interiorly of the envelope and respectively arranged adjacent to the opposite ends of the anode structure for establishing a unidirectional magnetic field extending axially through the interaction space, and a pair of external magnetic pole pieces disposed exteriorly of the envelope and respectively arranged adjacent to the internal pole pieces and in surrounding relation therewith and extending radially outwardly therefrom, each one of the internal pole pieces cooperating with the adjacent one of the external pole pieces to provide a composite pole piece, the dimensions of the composite pole pieces normal to the axis of the interaction space being substantially greater than the gap between the internal pole pieces axially through the interaction space.

Another object of the invention is to provide a crossed-field discharge device of the type set forth, wherein the portions of the wall of the envelope disposed between adjacent ones of the pole pieces in each of the composite pole pieces is of lesser thickness than the remaining portions of the wall of the envelope to decrease the magnetic reluctance between the adjacent ones of the pole pieces in each of the composite pole pieces.

Another object of the invention is to provide a crossed-

field discharge device of the type set forth wherein each of the internal pole pieces and each of the external pole pieces has an axially extending annular flange thereon disposed against the envelope, the flange on each of the internal pole pieces being disposed in radial alignment with the flange of the adjacent one of the external pole pieces.

Another object of the invention is to provide a crossed-field discharge device of the type set forth wherein each of the internal magnetic pole pieces has a generally circular periphery and each of the external magnetic pole pieces has a generally circular periphery, the internal pole pieces also preferably being disposed respectively at the opposite ends of the envelope and providing the end caps therefor.

In connection with the foregoing object, it is another object of the invention to provide an improved crossed-field discharge device of the type set forth wherein the ratio between the diameter of the composite pole pieces normal to the axis of the interaction space and the gap between the internal pole pieces axially through the interaction space is in the range from about 2.0:1 to about 2.5:1.

A further object of the invention is to provide a microwave assembly incorporating therein the improved crossed-field discharge device of the present invention, the device also being provided with a plurality of radially extending cooling fins mounted on the envelope in good thermal contact therewith, a pair of annular field coils disposed with the axes thereof in alignment with the longitudinal axis of the interaction space and respectively arranged adjacent to the opposite ends of the device for establishing a unidirectional magnetic field therebetween, a pair of magnetic yokes respectively arranged about the field coils and each including an inner section extending longitudinally through the opening in the associated field coil and magnetically coupled to the adjacent one of the internal pole pieces, an end section arranged at the outer end of the inner section and magnetically coupled thereto and extending radially outwardly therefrom beyond the periphery of the associated field coil and the cooling fins, a pair of outer sections disposed on opposite sides of the associated field coil and magnetically coupled to the end section and extending toward the device and terminating at points spaced outwardly and well away from the associated external pole piece, and side walls of non-magnetic material interconnecting the opposed pairs of the outer sections, the end sections and the outer sections and the side walls cooperating to provide a box-like structure open on two opposed sides thereof and defining a passage for cooling air passing therethrough and over the cooling fins and around the device to cool the same.

A still further object of the invention is to provide a microwave assembly of the type set forth wherein the cooling fins and the end sections have substantially rectangular peripheries and the outer sections are disposed on opposed sides of the rectangular end sections, the cooling fins being formed of copper and the side walls being formed of aluminum.

Further features of the invention pertain to the particular arrangement of the parts of the crossed-field discharge device and the mounting thereof in the microwave assembly, whereby the above-outlined and additional operating features thereof are attained.

The invention, both as to its organization and method of operation, together with further objects and advantages thereof, will best be understood by reference to the following specification when taken in connection with the accompanying drawings, in which:

FIGURE 1 is a view in vertical section through a microwave assembly incorporating therein a crossed-field dis-

charge device of the present invention, there being illustrated and associated with the device magnetic field coils therefor and the magnetic return structure and air duct housing therefor and the coupler and filter construction used therewith;

FIG. 2 is an enlarged view in vertical section through the crossed-field discharge device illustrated in FIG. 1;

FIG. 3 is a view in horizontal section through the assembly of FIG. 1 along the line 3—3 thereof;

FIG. 4 is a fragmentary view in horizontal section through the device of FIG. 2 along the line 4—4 thereof; and

FIG. 5 is a view in vertical section through the device of FIGS. 1 and 2 and illustrating more fully the relationship between the diameter of the composite magnetic pole pieces and the length of the gap between the pole pieces axially through the interaction space.

Referring to FIGS. 1 and 2 of the drawings, there is illustrated a microwave generator 10 embodying the features of the present invention, the microwave generator 10 more particularly including the improved crossed-field discharge device 100 of the present invention. The device 100 comprises an anode structure 101 including a sleeve 102 and a pair of anode members 110, a cathode structure 150, a pair of opposed pole pieces 130, an upper end structure 180 and a lower end structure 190.

The anode structure 101 is essentially annular in shape and is confined within the interior of the sleeve 102 (see FIGS. 2 and 5), the sleeve 102 being generally tubular and having a circular cross section at all points therewith, the outer surface 103 thereof being cylindrical. The inner surface 104 of the sleeve 102 is also cylindrical in shape and has at each end thereof a recess to define upper and lower end walls 102 and upper and lower side walls 106 of reduced thickness, the end walls 105 being essentially annular in shape and disposed parallel to each other and normal to the axis of the device 100 the side walls 106 being annular in shape and extending axially of the device 100. Mounted on the sleeve 102 at essentially the midpoint thereof and extending outwardly therefrom is an exhaust tubulation 107 hermetically sealed thereto and communicating with the interior thereof, the exhaust tubulation 107 being useful to evacuate the device 100, the interior of the device 100 being evacuated to a high degree and being hermetically sealed as will be explained more fully hereinafter. Also mounted on the outer surface 103 of the sleeve 102 is a stacked array of cooling fins 108, each of the cooling fins 108 being provided with an annular flange 109 that extends around the sleeve 102 and is fixedly secured thereto as by brazing. It will be understood that the sleeve 102 and the fins 108 are formed of a metal having good thermal conductivity, the preferred material being copper, thereby to accommodate the conduction of heat from the device 100 outwardly therefrom and into the fins 108. The shape of the fins 108 is substantially rectangular so that they fit within a box-like structure 200 disposed therearound, there preferably being provided means for passing a cooling fluid, such as a stream of air, through the box-like structure 200 and over the fins 108 to effect cooling thereof and a consequent removal of heat from the device 100 during the operation thereof.

Disposed within the sleeve 102 and also forming a part of the anode structure 101 are the two anode members 110. Referring particularly to FIGS. 2, 4 and 5, there is illustrated in detail the construction of the anode members 110. As illustrated, each anode member 110 is generally annular in shape and includes a body portion 111 disposed at one end thereof (the upper end as viewed in FIG. 2), the body portion 111 having an outer end wall 112 at one end thereof connecting with an annular outer wall 113 having an outer diameter only slightly less than the inner diameter of the sleeve 102, and specifically the inner surface 104 thereof, whereby the anode member 110 can fit within the sleeve 102 and ultimately is connected thereto as by brazing. The end of the body portion 111 op-

posite the end wall 112 is cut away or recessed to provide an annular inner wall 114 extending therearound and concentric with the annular outer wall 113 but having a substantially smaller diameter, the walls 113 and 114 being joined by an annular end wall 115 disposed parallel to the outer end wall 112 and normal to the walls 113 and 114; the other end of the inner wall 114 connects with an inner end wall 116 that defines the other end of the body portion 111, the end wall 116 being disposed in a plane parallel to the end walls 112 and 115 and normal to the walls 113 and 114.

There is provided interiorly of the anode member 110 and extending the length of the body portion 111 a plurality of axially extending anode segments 117 that project radially inwardly into the axially extending space within the anode member 110 and providing therebetween a corresponding plurality of axially extending anode recesses 122, fifteen of the anode segments 117 and fifteen of the corresponding recesses 122 being provided in the anode member 110 as illustrated. Each of the anode segments 117 has an axially extending inner surface 118 and a pair of outwardly directed side walls 119 on the opposite sides thereof, the circumferential extent of the inner surface 118 being substantially less than the radial extent of the associated side walls 119. The outer ends of adjacent pairs of the side walls 119 are joined by an outer wall 121, whereby the recesses 122 are defined by the associated side walls 119 and the associated outer wall 121, the side walls 119 of each recess 122 converging inwardly and being disposed substantially normal to the associated outer walls 121.

The anode member 110 further has thereon and integral therewith fifteen rods or vanes 125, each of the rods 125 being integral with and extending longitudinally from one of the anode segments 117. More specifically, the inner surface 118 of each of the anode segments 117 extends forwardly beyond the inner end wall 116 and substantially parallel to the axis of the anode member 110 and forms the inner surface of the associated rod 125. A portion of the side walls 119 on the anode segment 117 also extends forwardly beyond the inner end wall 116 to provide the radially extending sides of the associated rod 125, the inner surface 118 and the side walls 119 terminating at an end 126 disposed substantially normal to the axis of the anode member 110. An outer surface 127 is provided for each of the rods 125, the outer surface 127 extending from the inner end wall 116 forwardly to the rod 126; more specifically, the inner end of the outer surface 127 joins the inner end wall 116 at a point spaced radially inwardly away from the adjacent outer walls 121 (see FIG. 4) and tapers inwardly toward the associated inner surface from the end wall 116 to the rod end 126.

The anode members 110 are also formed of a metal having good thermal conductivity, the preferred material being copper. The sleeve 102 and the anode members 110 also must have good electrical conductivity, the copper providing the necessary good electrical conductivity as well as the good thermal conductivity. As illustrated in FIGS. 2 and 5, one of the anode members 110 is disposed in the upper portion of the sleeve 102 with the body portion 111 thereof disposed upwardly and with the rods 125 thereof extending downwardly; the other one of the anode members 110 is disposed in the lower portion of the sleeve 102 with the body portion 111 thereof disposed downwardly and with the rods 125 thereof extending upwardly. As is also illustrated in FIG. 4, the anode members 110 are rotated slightly with respect to each other so that the anode rods 125 on one of the anode members 110 are disposed in the center of the recesses 122 of the other one of the anode members 110, and conversely the anode rods 125 on the other one of the anode members 110 are disposed in the center of the recesses 122 of the one anode member 110. In this arrangement, there is one of the anode rods 125 disposed in each of the anode

recesses 122 and equidistantly spaced from the adjacent anode segments 117, all as is diagrammatically illustrated in FIG. 4.

The sleeve 102 and the anode members 110 also cooperate to provide an outer axially extending space 120, the space 120 being annular in shape and bounded on the outer portion by the inner wall 104 of the sleeve 102 and on the inner portion by the inner walls 114 and at the upper and lower ends by the end walls 115. The interior of the anode members 110 form a second or inner axially extending space within which is disposed the cathode structure 150, the space between the outer surface of the cathode structure 150 and the spaced facing surfaces 118 defining an annular axially extending interaction space 160. Furthermore, the inner end walls 116 are spaced apart to provide therebetween a radially extending annular passage 123 interconnecting the outer space 120 at the mid-portion thereof to the inner axially extending space at the mid-portion thereof and to the interaction space 160 at the mid-portion thereof.

The cathode structure 150 is provided in the axially extending space defined by the anode members 110, the cathode structure 150 including a cylindrical metal wall 151 (see FIG. 4) arranged with the axis thereof disposed at the axis of the device 100, the wall 151 being formed of a heat resistant and electrically conducting metal, the preferred material of construction being nickel. Mounted on each end of the wall 151 is a cathode end 152, the cathode ends 152 being substantially identical in construction, whereby the same reference numerals have been applied to like parts of both. Referring to the upper cathode end 152, it includes a substantially flat annular center plate 153 carrying on the outer edge thereof an axially directed annular inner flange 154 carrying on the inner end thereof an outwardly directed flat flange 155; the outer periphery of the flange 155 carries a mounting flange 156 thereon extending outwardly and disposed within the adjacent end of the wall 151 and suitably secured thereto as by welding. The outer edge of the flange 156 carries a radially and outwardly extending shield flange 157 that extends radially outwardly beyond the wall 151 and overlies the adjacent end of the interaction space 160. Each center plate 153 has a central opening 158 therein, the lower cathode end 152 carrying on the inner edge and surrounding the opening 158 therein a center end flange 159. The cathode ends 152 are also preferably formed of nickel. The upper cathode end 152 is mechanically and electrically connected to a cathode stud 167, the cathode stud 167 being generally circular in cross section and having at the lower end thereof a reduced diameter portion 168 that extends through the opening 158 in the cathode end 152 and is fixedly secured thereto as by a pair of outwardly directed flanges 169. It will be appreciated that the upper end of the cathode structure 150 is both electrically and mechanically connected to the stud 167.

The cathode wall 151 is provided with a sintered porous coating 161 impregnated with a suitable electron emissive oxide material, whereby upon heating of the cathode structure 150, the coating 161 readily emits electrons from the outer surface thereof. Referring particularly to FIG. 4, it will be seen that the coating 161 is shaped to provide a plurality of outwardly extending projections 162 each having outwardly converging side walls joining a generally circumferentially arranged outer surface 163, a space 164 being provided between the adjacent projections 162. As illustrated, the circumferential extent of the outer surface 163 is substantially equal to the space 164 between the adjacent projections 162. The preferred range of the circumferential extent of each of the outer surfaces 163 is approximately 25% to approximately 60% of the circumferential distance between the centers of adjacent outer surfaces 163. The number of projections 162 provided on the coating 161 is equal to the sum of the number of the anode segments 117 and the

number of cooperating rods 125, whereby there are thirty of the projections 162 provided upon the coating 161. The outer surfaces of the coating 161 together with the inner surfaces 118 on the anode members 110, define the interaction space 160 disposed therebetween in which the emitted electrons from the coating 161 interact with the electrical fields and the magnetic fields disposed between the anode structure 101 and the cathode structure 150. The projections 162 combine with the anode segments 117 and with the rods 125 to provide a preferred distribution of the several fields within the interaction space 160 of the device 100 that results in more desirable operating characteristics thereof. One particularly desirable result of the shape of the coating 161 is the minimized back heating of the cathode structure 150, the desirable emitted electrons emanating from the projections 162, and the undesirable emitted electrons emanating from the space 164 between the projections 162, thereby to facilitate the emission of desirable electrons and to suppress the emission of undesirable electrons.

It further will be noted from FIG. 4, that the center line of each projection 162 is circumferentially displaced relative to the center line of its corresponding anode segment 117 or its corresponding rod 125, as the case may be; more specifically, the center lines of the projection 162 are displaced in a clockwise direction a circumferential distance equal to approximately 40% of the circumferential spacing between the center lines of an adjacent anode segment 117 and an adjacent rod 125 (for example 5° rotation for a 12° spacing or a percentage of 41.8% as illustrated). The circumferential displacement of the projections 162 with respect to the corresponding anode segments or rods is preferably in the range between 0% and approximately 45% of the circumferential spacing between adjacent anode segments and rods, the preferred range being between approximately 25% and 45% of the spacing between adjacent anode segments and rods, a still more preferred range being between approximately 35% and 45% of the spacing between adjacent anode segments and rods. Furthermore, the displacement is on the downstream side, i.e., in the direction of normal initial electron flow from the projections 162. It also will be noted that the electron emissive coating 161 is confined between the outer end walls 112 of the anode members 110, the cathode structure 150 being carefully centered with respect to the anode members 110, whereby each of the cathode projections 162 extends axially of the device 100 parallel to the axis thereof and confined between the outer end walls 112.

The radial dimension of each of the projections 162 varies from end to end of the cathode structure 150. Adjacent to the outer ends of the cathode structure 150, the radial dimensions of each of the projections 162 is preferably greater than about 20% of the spacing between the anode surfaces 118 and the coating 161 on the cathode structure 150. At the longitudinal midpoint of the emissive coating 161, an area 166 of reduced radial dimension is provided, the radial extent of the projections 162 being substantially nil and in certain instances the coating 161 being completely removed at the center reduced portion 166; the portion 166 is opposite the annular passage 123 between the anode members 110 and is provided at this point to match impedances at this area in the device 100. There further is provided an intermediate reduced portion 165 between the center reduced portion 166 and each of the outer ends of the cathode structure 150, the intermediate reduced portions 165 having roughly one-half of the radial extent of the projections 162 therein that are found at the outer ends of the coatings 161. The longitudinal extent of the outer coating portions is substantially equal to the longitudinal extent of the intermediate reduced portions 165, which is in turn substantially equal to the longitudinal extent of the center reduced portion 166. In a typical construction of the coating 161, the

difference in the thickness of the coating is approximately 5 mils from one section to the adjacent section of the coating 161.

As illustrated, the cathode structure 150 is of the indirectly heated type, and accordingly, there has been provided within the cathode wall 151 a heater 176 in the form of a coiled filament extending substantially the entire length of the cathode wall 151 and spaced inwardly a short distance from the inner surface thereof. The upper end of the heater 176 as viewed in FIG. 2 has an outer end or terminal 177 that extends outwardly into an opening in the lower end of the cathode stud 167, and specifically through an annular opening in the reduced portion 168 thereof and is mechanically and electrically connected to the cathode stud 167, whereby the cathode structure 150 and the heater 176 are both mechanically and electrically connected to the cathode stud 167. The lower end of the heater 176 has an outer end or terminal 178 that extends into an opening in the upper end of a conductor 197 and is mechanically and electrically secured thereto. The conductor 197 is preferably formed of copper and extends outwardly and into a threaded connector 196. It will be noted that the heater terminal 178 is spaced from and electrically insulated with respect to the lower end of the cathode structure 150.

Mounted within the outer ends of the anode sleeve 102 and forming end walls for the device 100 are two internal pole pieces 130, the internal pole pieces 130 being identical in construction, whereby the same reference numerals have been applied to like parts of both of the internal pole pieces 130. The internal pole pieces 130 are formed of a material having high magnetic permeability, the preferred material being a low carbon steel, and are copper plated to render the outer surfaces thereof highly conductive to RF energy. As illustrated, each of the internal pole pieces 130 is generally cylindrical in shape including a first substantially flat inner plate 131 disposed centrally thereof and disposed in a plane substantially normal to the longitudinal axis of the device 100 and in longitudinal alignment with the interaction space 160. Disposed about the periphery of the inner plate 131 and integral therewith is a first annular coupling flange 132 extending outwardly therefrom and carrying on the outer edge thereof an outwardly directed outer plate 133 that is substantially flat and lying in a plane normal to the axis of the device 100 and being in longitudinal alignment with the adjacent end of the outer axially extending space 120. The outer edge of the outer plate 133 carries a annular and outwardly extending mounting and magnetic coupling flange 134 that has an outer diameter slightly less than the inner diameter of the associated recessed end of the anode sleeve 102 to be received therein and hermetically sealed thereto. Finally, there is provided centrally of each of the inner plates 131 a circular opening 135 in general longitudinal alignment with the adjacent end of the cathode structure 150, and specifically the adjacent end of the cathode wall 151, the opening 135 receiving the terminals of the cathode structure and heater therethrough. Preferably the internal pole pieces 130 are each formed of a single sheet of low carbon steel shaped as described by a stamping operation, thereby to provide accurate dimensions therefor together with an inexpensive manufacture thereof.

Mounted about the outer ends of the anode sleeve 102 and in general lateral alignment with the internal pole pieces 130 are two external pole pieces 140, the external pole pieces 140 being identical in construction, whereby the same reference numerals have been applied to like parts of both of the external pole pieces 140. The external pole pieces 140 are formed of a material having high magnetic permeability, the preferred material being a low carbon steel, and are copper plated to render the assembly thereof to the anode sleeve 102 readily possible by a brazing operation. As illustrated, each of the external pole pieces 140 is generally circular in shape and each in-

cludes a first substantially flat plate 141 disposed in a plane substantially normal to the longitudinal axis of the device 100 and disposed in substantially the same plane as the outer plate 133 of the associated internal pole piece 130. The outer plate 141 has an opening centrally thereof circular in shape and having a diameter to receive therethrough the adjacent end of the anode sleeve 102. Disposed about the periphery of the opening in the center of the outer plate 141 and integral therewith is an annular coupling flange 144 extending normal thereto and surrounding the adjacent end of the anode sleeve 102, the coupling flange 144 extending from the associated outer plate 141 in the same direction that the coupling flange 132 of the adjacent internal pole piece 130 extends from the associated outer plate 133 thereof. Preferably the external pole pieces 140 are each formed of a single sheet of low carbon steel shaped as described by a stamping operation, thereby to provide accurate dimensions thereof together with an inexpensive manufacture thereof.

As is illustrated in FIGS. 2 and 5 of the drawings, the upper internal pole piece 130 and the upper external pole piece 140 cooperate to provide an upper composite pole piece 145; and the lower internal pole piece 130 and the lower external pole piece 140 cooperate to provide a lower composite pole piece 145. Although the pole pieces 130 and 140 in each of the composite pole pieces 145 are not in direct physical and magnetic contact one with the other, there is strong magnetic coupling therebetween, it being pointed out that the sleeve 102 has a reduced wall thickness 106 disposed between the adjacent ones of the pole pieces 130 and 140. Furthermore, the magnetic coupling flange 134 on each of the internal pole pieces 130 is disposed concentrically within and adjacent to the magnetic coupling flange 144 on the associated external pole piece 140, thereby to provide a large mass of magnetically permeable material that constitutes a low reluctance path for magnetic lines of force between the adjacent ones of the pole pieces 130 and 140.

It further will be noted from FIG. 5 that the external diameter D of the composite pole pieces 145 is substantially greater than the gap between the inner plates 131 of the internal pole pieces 130, and thus the gap G through the interaction space 160; more specifically, the ratio between the external diameter D of each composite pole piece 145 and the gap G between the internal pole pieces 130 is approximately 2.25:1. Preferably, this ratio between the external diameter D of the composite pole pieces 145 and the length of the magnetic gap G between the internal pole pieces 130 is in the range from about 2.0:1 to about 2.5:1. It has been found that when the parts have the dimensions and ratio of dimensions noted, a very strong and uniform field is provided through the interaction space 160, all provided in a structure that has small dimensions and that is inexpensive to manufacture.

An upper end structure 180 is provided at the upper end of the device 100 as viewed in FIG. 2 and a lower end structure 190 is provided at the lower end of the device 100, the end structures 180 and 190 serving to provide a hermetic seal between the associated internal pole pieces 130 and the associated connections to the cathode structure 150 and/or the heater 176, as the case may be. The upper end structure 180 includes a short tube 181 having the lower end thereof disposed within the opening 135 in the upper internal pole piece 130 and suitably hermetically secured thereto as by brazing and extending upwardly therefrom substantially concentric with the longitudinal axis of the device 100 and the axis of the cathode stud 167. The upper end of the tube 181 receives therein the lower end of an annular insulator 182 which is formed, for example, of a good electrically insulating ceramic, the tube 181 being hermetically sealed to the insulator 182. There is provided about the cathode stud 167 at the portion thereof adjacent to the reduced portion 168 a ring 183 that fits within a recess in the lower end of the insulator 182. Surrounding the upper

end of the insulator 182 and the adjacent portion of the cathode stud 167 is a cap 185, the cap 185 being generally annular in shape and including an annular flange 186 surrounding an outer periphery of the upper end of the insulator 182 and being hermetically sealed thereto. Integral with the upper edge of the outer flange 186 is an inwardly directed flange 187 carrying on the inner edge thereof an outwardly directed annular inner flange 188 surrounding the adjacent portion of the stud 167 and hermetically sealed thereto as by brazing. It is pointed out that the sleeve 181 and the cap 185 are both formed of a material that can be readily secured both to a metal surface and to a ceramic surface, the preferred material being "Fernico" alloy, a typical composition being 54% iron, 28% nickel and 18% cobalt. It will be seen that the upper end structure 180 forms a good hermetic seal that also provides electrical insulation between the upper internal pole piece 130 and the output conductor in the form of the cathode stud 167, the end structure 180 likewise providing the necessary mechanical support for the cathode structure 150 to position it within the anode structure 101.

In the lower end structure 190, a ceramic insulator 191 is provided that is annular in shape and has an outer diameter just slightly less than the diameter of the opening 135 in the lower internal pole piece 130 and an inner diameter just slightly greater than the external diameter of the centering flange 159 on the lower cathode end 152, whereby the insulator 191 serves to center the lower end of the cathode structure 150 with respect to the lower internal pole piece 130. The insulator 191 extends outwardly well beyond the lower internal pole piece 130 and there is provided a seal member 192 annular in shape and surrounding the insulator 191, the seal member 192 including a mounting flange 193 fixedly secured as by brazing to the outer surface of the inner plate 131 on the lower internal pole piece 130, the mounting flange 193 having integral therewith an annular wall 194 carrying an outer flange 195 that is inwardly directed and surrounds and is secured to the outer wall of the insulator 191. The seal member 192 is made of the same material as the sleeve 181 and the cap 185 and is hermetically sealed both to the lower internal pole piece 130 and the insulator 191. The outer end of the insulator 191 carries thereon a second seal member 198 that overlies the outer end thereof and is suitably secured as by brazing to the connector 196, the seal member 198 including an annular flange 199 surrounding the outer end of the insulator 191 and sealed thereto. The seal member 198 is formed of the same material as the seal member 192 and is hermetically sealed both to the insulator 191 and the connector 196. The lower end structure 190 therefore serves hermetically to seal the lower end of the device 100 and also provides electrical insulation between the lower end of the cathode structure 150 and the associated internal pole piece 130 and the heater 176, all while providing for the mechanical support of the lower end of the cathode structure 150 and the lower end of the heater 176.

When the device 100 is incorporated as a crossed-field discharge device in a microwave circuit, the composite pole pieces 145 arranged adjacent to the opposite ends of the anode structure 101 are utilized for establishing a unidirectional magnetic field extending axially through the several spaces within the anode structure 101, and specifically through the axially extending space 120 and through the interaction space 160, as well as the annular passage 123 and the various spaces between the anode members 110. To this end a pair of magnet coils 210 and 215 has been provided, the magnet coil 210 being disposed about the upper end of the device as viewed in FIG. 1 and the magnet coil 215 being disposed about the lower end of the device 100 as viewed in FIG. 1. The magnet coils 210 and 215 are both shaped as a torous, are wound of electrically conductive wire, and as illustrated are disposed respectively about magnet yokes 211

and 216, respectively, that include inner annular sections 212 and 217, respectively, that are each in the form of a cylinder disposed within the opening in the associated magnet coil. There further are provided outwardly extending end sections or flanges 213 and 218, respectively, about the outer ends of the inner sections 212 and 217 and secured respectively thereto. It will be understood that the magnet yokes 211 and 216, including the annular sections 212 and 217 and the end sections 213 and 218, are all formed of metals having a high magnetic permeability, such as soft iron and low carbon steel, whereby when the magnet coils 210 and 215 are energized, a strong and uniform unidirectional magnetic field is established between the composite pole pieces 145 and extending axially through the spaces within the device 100, and specifically extending axially through the outer axially extending space 120 and the interaction space 160 therein.

The circuit for energizing the coils 210 and 215 can be traced with reference to FIG. 1 from a DC power supply conductor 207a to a DC input terminal 207 for the generator 10 to which is connected one terminal of the upper magnet coil 210. The other terminal of the upper magnet coil 210 is connected by a conductor 214 to one terminal of the lower magnet coil 215, and the other terminal of the lower magnet coil 215 is connected by a conductor 219 to one of the cooling fins 108, whereby the input terminal 207 is connected via the upper magnet coil 210, the conductor 214, the lower magnet coil 215, the conductor 219 and the cooling fin 108 to the anode sleeve 102 of the device 100. The flow of current through the magnet coils 210 and 215 serves to produce the unidirectional magnetic field in the various spaces of the device 100, and specifically in the outer space 120 and the interaction space 160 thereof.

The crossed-field discharge device 100 and the magnet coils 210 and 215 therefor, together with the other associated parts thereof, are all housed within the box-like structure generally designated by the numeral 200, see FIG. 1 particularly. The box-like structure 200 includes an upper end plate 201 and a lower end plate 205, the end plates 201 and 205 being substantially rectangular in shape and having dimensions slightly greater than the corresponding dimensions of the rectangular cooling fins 108. The end plate 201 is provided on one pair of sides thereof with integral side flanges 202, the side flanges 202 being disposed substantially normal to the end plate 201 and extending toward the lower end plate 205 and terminating just slightly below the lower edge of the upper magnet coil 210. The end plate 205 is provided on one pair of opposed sides thereof with integral side flanges 206, the side flanges 206 being disposed substantially normal to the end plate 205 and extending upwardly toward the upper end plate 201 and terminating just slightly above the upper edge of the lower magnet coil 215. Enclosing the space between the opposed free edges of the side flanges 202 and 206 are side walls 203, the side walls 203 being disposed inside of the associated ones of the side flanges 202 and 206 and being suitably secured thereto. The other sides of the end plates 201 and 205 are free, whereby the associated sides of the box-like structure 200 are open to receive therethrough a stream of cooling fluid, such as air, that passes around the magnet coils 210 and 215 and around the cooling fins 108, it being noted that the external pole pieces 140 also provide a certain amount of cooling for the device 100. In certain instances, it is desired to cover the open sides of the box-like structure 200 with a foraminous sheet, such as a screen (not shown) in order to prevent inadvertent contact with the high potentials present in the box-like structure 200.

In accordance with the present invention, the end plates 201 and 205 and the side flanges 202 and 206 integral therewith are formed of a material that has a high magnetic permeability, such as soft iron and low carbon steel, whereby these parts form a portion of a magnetic

return path for the magnetic circuit. The side walls 203, however, are preferably formed of a material having a low magnetic permeability, a preferred material being aluminum, whereby the side walls 203 provide high reluctance paths for magnetic force lines. As a result, the set of opposed sides of the box-like structure 200 on which are disposed the side walls 203 also appear to be open to the magnetic circuit as are the other set of opposed sides of the box-like structure 200, whereby there is substantially no distortion of the magnetic field within the device 100 due to the presence of the materials of construction of the box-like structure 200. As a result, a much more uniform magnetic field is provided in the interaction space 160 than would be the case if the side walls 203 were formed of a material having a high magnetic permeability, whereby to provide a low reluctance magnetic path on one set of opposed sides of the box-like structure 200 while providing a high reluctance magnetic path on the other set of opposed sides of the box-like structure 200. In this connection it is also pointed out that the external pole pieces 140 tend to shunt the leakage field that would otherwise tend to distort the magnetic field in the interaction space, the use of non-magnetic material for the side plates 203 tending to minimize leakage flux which would otherwise tend to saturate the magnetic yokes 211 and 216 and reduce the field intensity in the interaction space 160.

Referring now to FIG. 1 of the drawings, the manner in which the crossed-field discharge device 100 is incorporated in the generator 10 will be described in further detail. A tubular conductor 204 is provided formed of a material that is electrically conductive, the conductor 204 having the lower end thereof received within the upper internal pole piece coupling flange 132 in telescoping relation therewith and is electrically connected thereto, the conductor 204 also being disposed within the upper magnet yoke 211 and extending upwardly and beyond the upper end thereof. As is illustrated in both FIGS. 1 and 2, the cathode stud 167 at the upper end of the crossed-field discharge device 110 has the outer end thereof disposed below the outer end of the associated magnet yoke 211. The cathode stud 167 and the conductor 204 form a coaxial transmission line that provides output RF terminals for the generator 10, the terminals having applied therebetween the output RF energy from the generator 10. In addition, the outer conductor 204 has applied thereto the B⁺ potential from the conductor 207a which is connected thereto via the input terminal 207, the upper magnet coil 210, the conductor 214, the lower magnet coil 215, the conductor 219, the cooling fin 108, the anode sleeve 102 and the upper internal pole piece 130, the upper internal pole piece 130 being directly connected to the lower end of the outer conductor 204 as illustrated. Accordingly, it will be seen that the outer conductor 204 not only serves as one of the RF terminals for the device 100 but also is in direct electrical connection with the B⁺ potential on the anode sleeve 102. Likewise, the cathode stud 167 not only has the RF output energy thereon but has applied thereto both the B⁻ potential for the cathode 150 of the device 100 and the low voltage AC potential for energizing the heater 176.

In order to accommodate the application to and the presence of the various potentials named on the output terminals 167 and 204 while preventing the introduction of RF energy into the power supply 51, and while preventing the application of the B⁺ and B⁻ potentials to the output terminals 231 and 241 provided, there has been provided a coupler and filter structure 230. Referring to FIG. 1, it will be seen that the coupler and filter structure 230 includes a first RF output terminal in the form of annular outer conductor 231 which is capacitively coupled to the conductor 204 by a coupler 232, the coupler 232 including a sleeve 233 of electrically insulating dielectric material, the sleeve 233 preferably being formed of a synthetic organic plastic resin, the preferred

resin being a tetrafluoroethylene resin sold under the trademark "Teflon." The insulating sleeve 233 is disposed around and firmly embraces the outermost end of the tubular conductor 204 and extends upwardly therebeyond; the lower end of the outer conductor 231 is in turn placed in telescoping relationship about the sleeve 233, the lower end of the conductor 231 telescopically overlapping the upper end of the conductor 204 for a distance equal to 1/4 of the wavelength of the frequency of operation of the generator 10 in order to provide a portion of a second harmonic filter.

An opening is provided in the side wall of the conductor 204 adjacent to the upper end of the generator 10, and joining the conductor 204 and surrounding the opening in the side wall thereof is a second annular conductor 234 that is suitably secured as by welding to the conductor 204 and extends laterally therefrom and to the right as viewed in FIG. 1 with the longitudinal axes of the conductors 204 and 234 disposed substantially normal to each other. Disposed in the conductor 204 adjacent to the junction thereof with the conductor 234 is a pair of annular insulators 235 and 236 substantially filling the conductor 204 and spaced apart a short distance from each other, the insulators 235 and 236 being formed of an electrically insulating dielectric material, the preferred material being a synthetic organic plastic resin, the preferred resin being a tetrafluoroethylene resin sold under the trademark "Teflon." The lower insulator 235 has an opening centrally therein that receives therethrough a portion of a bullet 237 having on the lower end thereof a plurality of spring fingers 237a that resiliently grip the upper end of the cathode stud 167 to form a good electrical contact and mechanical interconnection therewith, a laterally extending flange 237b extending around the bullet 237 and being disposed below and in supporting relationship with the insulator 235.

Extending upwardly through an opening in the center of the bullet 237 is a probe 238 in the form of a solid rod of electrically conductive material, the preferred material being copper. The probe 238 passes through an opening in the center of the insulator 236 and upwardly therebeyond, the insulator 236 having an upstanding flange 236a surrounding the probe 238. A suitable fastener such as a screw 239 is provided at the lower end of the probe 238 and threadedly engages a complementarily threaded opening at the lower end thereof, the head of the screw 239 overlying the lower surface of the bullet 237. Arranged about and in telescoping relationship with the upper end of the probe 238 is an annular inner conductor 240 that has the lower end resting upon the insulator 236 and surrounding the upstanding flange 236a thereon, the upper end of the conductor 240 having an enlarged section 240a thereon that extends upwardly well beyond the probe 238 and telescopically receives therein a second tubular inner conductor 241 that serves as an RF output terminal for the coupler and filter structure 230, whereby the conductors 231 and 241 provide the RF output terminals for the coupler and filter structure 230. A capacitive coupling is provided between the probe 238 and the conductors 240 and 241 by a coupler 242 including an annular washer 243 formed of an electrically insulating dielectric material, the preferred material being a synthetic organic plastic resin, the preferred resin being a tetrafluoroethylene resin sold under the trademark "Teflon." The washer 243 surrounds the upper end of the probe 238 and is seated in the enlarged portion 240a at the upper end of the conductor 240 and serves fixedly to position the upper end of the probe 238 with respect to the conductors 240 and 241. A second fastener in the form of a screw 239 is provided in the upper end of the probe 238 and has a threaded shank threadedly engaged in a complementarily shaped threaded opening in the upper end of the probe 238, the head of the screw 239 engaging the upper surface of the insulating washer 243, whereby the two opposed screws 239 serve fixedly to interlock the insulators 235

and 236, the bullet 237, the conductor 240 and the insulating washer 243.

The B- potential and the low voltage AC filament supply for the device 100 are connected to the probe 238 and thus to the device 100 through connections in the conductor 234, and specifically through a conductor 244 disposed within and concentric with the outer conductor 234. The conductor 244 carries on the left hand end thereof as viewed in FIG. 1 a connector 244a having an opening therein that receives therethrough the probe 238, whereby to make good electrical connection therewith. Disposed about the conductor 244 and between the outer conductor 234 and the inner conductor 244 is an annular insulator 245 formed of an electrically insulating dielectric material, the preferred material being a synthetic organic plastic resin, the preferred resin being a tetrafluoroethylene resin sold under the trademark "Teflon." Disposed to the left of the insulator 245 is an enlargement or flange 244b on the conductor 244, and disposed to the right of the insulator 245 is a cylindrical choke 246 in the form of a tubular conductor that surrounds and receives therethrough the conductor 244 arranged concentrically therewith, the insulator 245 having a laterally extending flange 245a surrounding the conductor 244 and extending in the lefthand end of the choke 246 to position the adjacent end of the choke 246 with respect to the conductor 244. A conductive nut 247 is provided about the conductor 244 adjacent to the righthand end thereof and including a flange 247a extending into the righthand end of the choke 246 to position the adjacent ends of the conductor 244 and the choke 246 with respect to each other. The righthand end of the conductor 244 is threaded as at 244c and threadedly engages an internally threaded opening in the nut 247 to lock the insulator 245 and the choke 246 against the flange 244b; the threaded end 244c is connected to an input terminal 208 formed of a conductive metal, the terminal 208 having an enlarged lefthand end 249 having a threaded opening therein to receive the adjacent threaded end 244c of the conductor 244. The terminal 208 extends outwardly to the right beyond the outer conductor 234 and is connected to a conductor 208a from the associated power supply, the conductor 208a carrying both the B- potential and the heater supply potential. Connected between the outer conductor 234 and the input terminal 208 is a filter capacitor 248 of the feed through type that is in the form of two layers of conductive foil between which are interposed layers of insulating film, the layers of conductive foil and insulating film being wound to form the capacitor 248, one terminal of the capacitor 248 being connected to the outer conductor 234 and the other terminal of the capacitor 248 being connected to the terminal 208.

As has been explained above, the inner conductor 204 and the outer conductor 231 telescopically overlap a distance equal to $\frac{1}{4}$ wavelength of the frequency of operation of the generator 10. In addition, the probe 238, the inner conductor 240 and the choke 246 are also constructed to have a length equal to $\frac{1}{4}$ wavelength of the frequency of operation of the generator 10. In the operation of the coupler and filter structure 230, the outer conductors 204-234 serve as a B+ input terminal, the conductor 204 being directly connected to the conductor 219 by which B+ potential is applied to the outer sleeve 102, and the terminal 208 services as the B- input terminal and is connected to the cathode 150 via the conductor 244, the probe 248, the bullet 237, and the cathode stud 167 (see FIG. 3 also), whereby to apply B- potential to the cathode 150. The terminal 208 also serves as an input terminal for the low voltage AC filament supply and is connected to one end of the heater 176 via the conductor 244, the probe 238, the bullet 237 and the cathode stud 167, whereby to apply low voltage AC potential to the upper end of the heater 176.

The connector 196 at the lower end of the device 110

(see FIG. 2) is connected to a filter capacitor of the feed through type, and more specifically is connected to the input terminal 209 that has the adjacent end thereof internally threaded and receives the threaded outer end of the terminal 196 therein. A tubular conductor 221 is provided formed of a metal that is electrically conductive, the conductor 221 having the upper end thereof received within the lower internal pole piece coupling flange 132 in telescoping relation therewith and being electrically connected thereto, the conductor 221 being disposed within the lower magnet yoke 216 and extending downwardly and beyond the lower end thereof. There is provided on the lower end of the conductor 221 a cover 222 formed of conductive metal and including a flange 224 surrounding and in telescoping relationship with the lower end of the conductor 221 and mechanically and electrically secured thereto. Disposed between the terminal 209 and the cover 222 is a filter capacitor 226 of the same type of construction as the filter capacitor 248 described above, one of the terminals of the filter capacitor 226 being connected to the cover 222 and the other terminal of the filter capacitor 226 being connected to the terminal 209, a flange 227 being provided on the exterior of the filter capacitor 226 in overlying relationship with the cover 222. The filter capacitor 226 serves to by-pass RF energy from the terminal 209 to the outer conductor 221 through the cover 222, thereby to prevent the introduction of RF energy into the associated power supply via the conductor 209a.

Further details of the construction and a more full explanation of the operation of the crossed-field discharge device 100 and of the lower filter 220 and the output coupler and filter structure 230 can be had by reference to the copending application for U.S. Letters Patent, Ser. No. 559,267, filed June 21, 1966 by James E. Staats, the disclosure of said application Ser. No. 559,267 being incorporated herein by reference.

The crossed-field discharge device of the above mentioned application Ser. No. 559,267 when incorporated in a large magnet structure has an operating efficiency of about 35%, but when that device is placed in a compact magnet structure, i.e., when the magnet coils were placed close to the magnetic pole pieces within the device, the efficiency was reduced to about 30%. However, when the same device of application Ser. No. 559,267 was equipped with the external pole pieces 140 of the present invention and was placed in the improved box-like structure 200 incorporating the side plates 203 of non-magnetic material, the efficiency thereof was increased to 40%, whereby it will be seen that the present invention presents a substantial increase in the efficiency of the crossed-field discharge device.

In view of the foregoing, it is apparent that there has been provided a crossed-field discharge device and microwave assemblies incorporating the same that are of improved connection and arrangement, and which fulfill all of the objects and advantages set forth above.

While there has been described what is at present considered to be the preferred embodiment of the invention, it will be understood that various modifications may be made therein and it is intended to cover in the appended claims all such modifications as fall within the true spirit and scope of the invention.

What is claimed is:

1. A crossed-field discharge device comprising an envelope, an anode structure disposed in said envelope and defining an axially extending space, an axially extending cathode structure disposed in said axially extending space and cooperating with said anode structure to define an axially extending annular interaction space therebetween, said cathode structure including an electron emissive element disposed within said anode structure and adjacent to the inner portion of said interaction space, a pair of internal identically constructed magnetic pole pieces disposed interiorly of said envelope and respectively ar-

ranged adjacent to the opposite ends of said anode structure for establishing a unidirectional magnetic field extending axially through said interaction space, and a pair of identically constructed external magnetic pole pieces disposed exteriorly of said envelope and respectively arranged adjacent to said internal pole pieces and in surrounding relation therewith and extending radially outwardly therefrom, each one of said internal pole pieces cooperating with the adjacent one of said external pole pieces to provide a composite pole piece, the dimensions of said composite pole pieces normal to the axis of said interaction space being substantially greater than the gap between said internal pole pieces axially through said interaction space.

2. The crossed-field discharge device set forth in claim 1, wherein the portions of the wall of said envelope disposed between the adjacent ones of said pole pieces in each of said composite pole pieces is of lesser thickness than the remaining portions of the wall of said envelope to decrease the magnetic reluctance between the adjacent ones of said pole pieces in each of said composite pole pieces.

3. The crossed-field discharge device set forth in claim 1, wherein said internal pole pieces are disposed at the opposite ends of said envelope and provide the end caps therefor.

4. The crossed-field discharge device set forth in claim 1, wherein each of said internal pole pieces has an axially extending annular flange thereon disposed against said envelope, each of said external pole pieces has an axially extending annular flange thereon disposed against said envelope; the flange on each of said internal pole pieces being disposed in radial alignment with the flange on the adjacent one of said external pole pieces.

5. A crossed-field discharge device comprising an envelope, an annular anode structure disposed in said envelope and defining an annular axially extending space, an axially extending annular cathode structure disposed in said axially extending space and cooperating with said anode structure to define an axially extending annular interaction space therebetween, said cathode structure including an electron emissive element disposed within said anode structure and adjacent to the inner portion of said interaction space, a pair of identically constructed annular internal magnetic pole pieces each having a generally circular periphery and disposed interiorly of said envelope and respectively arranged adjacent to the opposite ends of said anode structure for establishing a unidirectional magnetic field extending axially through said interaction space, and a pair of identically constructed annular external magnetic pole pieces each having a generally circular periphery and disposed exteriorly of said envelope and respectively arranged adjacent to said internal pole pieces and in surrounding relation therewith and extending radially outwardly therefrom, each one of said internal pole pieces cooperating with the adjacent one of said external pole pieces to provide a composite pole piece, the outermost diameter of said composite pole pieces normal to the axis of said interaction space being substantially greater than the gap between said internal pole pieces axially through said interaction space.

6. The crossed-field discharge device set forth in claim 5, wherein the ratio between the outermost diameter of said composite pole pieces normal to the axis of said interaction space and the gap between said internal pole pieces axially through said interaction space is in the range from about 2.0:1 to about 2.5:1.

7. The crossed-field discharge device set forth in claim 5, wherein each of said internal pole pieces has an axially extending annular flange thereon disposed against said envelope, each of said external pole pieces has an axially extending annular flange thereon disposed against said envelope, the flange on each of said internal pole pieces being disposed in radial alignment with the flange on the adjacent one of said external pole pieces.

8. The crossed-field discharge device set forth in claim 5, wherein the portions of the wall of said envelope disposed between adjacent pairs of the flanges on said pole pieces being of lesser thickness than the remaining portions of the walls of said envelope to decrease the magnetic reluctance between the adjacent ones of said pole pieces in each of said composite pole pieces.

9. The crossed-field discharge device set forth in claim 5, wherein said anode structure defines therein an outer annular axially extending space enclosed thereby and an inner axially extending space extending therethrough and a radially extending passage interconnecting said outer axially extending space and said inner axially extending space at the longitudinal midsection of said anode structure, said radially extending passage dividing said anode structure into a first anode section disposed adjacent to one end thereof and a second anode section disposed adjacent to the other end thereof, a plurality of axially extending anode segments on the inner surfaces of said anode sections and projecting radially into said inner axially extending space and providing a corresponding plurality of axially extending anode recesses therebetween, a plurality of axially extending first rods on said first anode section respectively disposed in the anode recesses in said second anode section and respectively spaced from the adjacent ones of said anode segments on said second anode section, and a plurality of axially extending second rods on said second anode section respectively disposed in the anode recesses in said first anode section and respectively spaced from adjacent ones of said anode segments on said first anode section.

10. A crossed-field discharge device comprising an annular sleeve, a pair of annular anode members disposed within said sleeve, a plurality of rods disposed adjacent to the inner surfaces of said anode members, said sleeve and said anode members being electrically connected at the opposite ends of said device and said rods being electrically connected to said anode members at the outer ends thereof, said sleeve and said anode members cooperating to define a first axially extending space therebetween and said anode members cooperating to define a second axially extending space therethrough and said anode members being spaced apart axially to provide a lateral passage therebetween interconnecting said axially extending spaces, each of said anode members having a plurality of radially extending anode segments on the inner surface thereof projecting radially into said second axially extending space and providing a plurality of axially extending anode recesses therebetween, said rods being respectively disposed in said anode recesses and respectively spaced from the adjacent ones of said anode segments, an axially extending cathode structure disposed in said second axially extending space and cooperating with said anode members to define an axially extending annular interaction space therebetween, said cathode structure including an electron emissive element disposed within said anode members and adjacent to the inner portion of said interaction space, a pair of identically constructed internal magnetic pole pieces disposed interiorly of said sleeve and respectively arranged adjacent to the opposite ends of said anode members for establishing a unidirectional magnetic field extending axially through said interaction space, and a pair of identically constructed external magnetic pole pieces disposed exteriorly of said sleeve and respectively arranged adjacent to said internal pole pieces and in surrounding relation therewith and extending radially outwardly therefrom, each one of said internal pole pieces cooperating with the adjacent one of said external pole pieces to provide a composite pole piece, the dimensions of said composite pole pieces normal to the axis of said interaction space being substantially greater than the gap between said internal pole pieces axially through said interaction space.

11. A microwave assembly comprising a crossed-field discharge device including an envelope, an anode struc-

ture disposed in said envelope and defining an axially extending space, an axially extending cathode structure disposed in said axially extending space and cooperating with said anode structure to define an axially extending annular interaction space therebetween, said cathode structure including an electron emissive element disposed within said anode structure and adjacent to the inner portion of said interaction space, a pair of internal magnetic pole pieces disposed interiorly of said envelope and respectively arranged adjacent to the opposite ends of said anode structure for establishing a unidirectional magnetic field extending axially through said interaction space, a pair of external magnetic pole pieces disposed exteriorly of said envelope and respectively arranged adjacent to said internal pole pieces and in surrounding relation therewith and extending radially outwardly therefrom, each one of said internal pole pieces cooperating with the adjacent one of said external pole pieces to provide a composite pole piece, the dimensions of said composite pole pieces normal to the axis of said interaction space being substantially greater than the gap between said internal pole pieces axially through said interaction space.

12. The microwave assembly set forth in claim 11, wherein said cooling fins are formed of copper, and said side walls are formed of aluminum.

13. The microwave assembly set forth in claim 11, wherein said cooling fins and said end sections have substantially rectangular peripheries, and said outer sections are disposed on opposed sides of said rectangular end sections.

14. A crossed-field discharge device comprising an envelope, an anode structure disposed in said envelope and defining an axially extending space, an axially extending cathode structure disposed in said axially extending space and cooperating with said anode structure to define an axially extending annular interaction space therebetween, said cathode structure including an electron emissive element disposed within said anode structure and adjacent to the inner portion of said interaction space, a pair of identically constructed internal magnetic pole pieces disposed interiorly of said envelope and respectively arranged adjacent to the opposite ends of said anode structure for establishing a unidirectional magnetic field extending axially through said interaction space, each of said internal magnetic pole pieces comprising an annular inner plate disposed in a plane substantially normal to the longitudinal axis of said device, a first annular axially extending flange disposed around the periphery of said inner plate integral therewith and extending outwardly

therefrom, an annular outer plate integral with the outer edge of said first flange and extending outwardly therefrom in a plane parallel to the plane of said inner plate and a second annular axially extending flange disposed around the periphery of said outer plate and integral therewith and extending outwardly therefrom, and a pair of identically constructed external magnetic pole pieces disposed exteriorly of said envelope and respectively arranged adjacent to said internal pole pieces and in surrounding relation therewith and extending radially outwardly therefrom, each one of said internal pole pieces cooperating with the adjacent one of said external pole pieces to provide a composite pole piece, the dimensions of said composite pole pieces normal to the axis of said interaction space being substantially greater than the gap between said internal pole pieces axially through said interaction space.

15. A crossed-field discharge device comprising an envelope, an annular anode structure disposed in said envelope and defining an annular axially extending space, an axially extending annular cathode structure disposed in said axially extending space and cooperating with said anode structure to define an axially extending annular interaction space therebetween, said cathode structure including an electron emissive element disposed within said anode structure and adjacent to the inner portion of said interaction space, a pair of identically constructed annular internal magnetic pole pieces each having a generally circular periphery and disposed interiorly of said envelope and respectively arranged adjacent to the opposite ends of said anode structure for establishing a unidirectional magnetic field extending axially through said interaction space, each of said internal magnetic pole pieces comprising an annular inner plate disposed in a plane substantially normal to the longitudinal axis of said device, a first annular axially extending flange disposed around the periphery of said inner plate integral therewith and extending outwardly therefrom, an annular outer plate integral with the outer edge of said first flange and extending outwardly therefrom in a plane parallel to the plane of said inner plate and a second annular axially extending flange disposed around the periphery of said outer plate and integral therewith and extending outwardly therefrom, and a pair of identically constructed annular external magnetic pole pieces each having a generally circular periphery and disposed exteriorly of said envelope and respectively arranged adjacent to said internal pole pieces and in surrounding relation therewith and extending radially outwardly therefrom, each one of said internal pole pieces operating with the adjacent one of said external pole pieces to provide a composite pole piece, the outermost diameter of said composite pole pieces normal to the axis of said interaction space being substantially greater than the gap between said internal pole pieces axially through said interaction space.

16. A crossed-field discharge device comprising an annular sleeve, a pair of annular anode members disposed within said sleeve, a plurality of rods disposed adjacent to the inner surfaces of said anode members, said sleeve and said anode members being electrically connected at the opposite ends of said device and said rods being electrically connected to said anode members at the outer ends thereof, said sleeve and said anode members cooperating to define a first axially extending space therebetween and said anode members cooperating to define a second axially extending space therethrough and said anode members being spaced apart axially to provide a lateral passage therebetween interconnecting said axially extending spaces, each of said anode members having a plurality of radially extending anode segments on the inner surface thereof projecting radially into said second axially extending space and providing a plurality of axially extending anode recesses therebetween, said rods being respectively disposed in said anode recesses and respectively spaced from the adjacent ones of said anode seg-

ments, an axially extending cathode structure disposed in said second axially extending space and cooperating with said anode members to define an axially extending annular interaction space therebetween, said cathode structure including an electron emissive element disposed within said anode members and adjacent to the inner portion of said interaction space, a pair of identically constructed internal magnetic pole pieces disposed interiorly of said sleeve and respectively arranged adjacent to the opposite ends of said anode members for establishing a unidirectional magnetic field extending axially through said interaction space, each of said internal magnetic pole pieces comprising an annular inner plate disposed in a plane substantially normal to the longitudinal axis of said device, a first annular axially extending flange disposed around the periphery of said inner plate integral therewith and extending outwardly therefrom, an annular outer plate integral with the outer edge of said first flange and extending outwardly therefrom in a plane parallel to the plane of said inner plate and a second annular axially extending flange disposed around the periphery of said outer plate and integral therewith and extending outwardly therefrom, and a pair of identically constructed external magnetic pole pieces disposed exteriorly of said
